UNITED STATES PATENT OFFICE.

WILLIAM H. FULCHER, OF STOCKTON, CALIFORNIA, ASSIGNOR OF ONE-HALF
TO J. JAMES TULLY, OF SAME PLACE.

EXCAVATOR.

SPECIFICATION forming part of Letters Patent No. 558,452, dated April 14, 1896.

Application filed December 10, 1895. Serial No. 571,690. (No model.)

To all whom it may concern:

Be it known that I, WILLIAM H. FULCHER, a citizen of the United States, residing at Stockton, in the county of San Joaquin and State 5 of California, have invented certain new and useful Improvements in Excavators; and I do hereby declare the following to be a full, clear, and exact description of said invention, such as will enable others skilled in the art to which 10 it most nearly appertains to make, use, and practice the same.

This invention relates to improvements in excavators and more particularly to ditch-excavators.

15 The objects which this present invention has in view are primarily to raise the earth at the forward end of the machine and deliver and tamp it firmly at the rear end, carrying it over the intervening space where 20 other work is being performed, and, secondarily, to provide means whereby this is accomplished with certainty and at the slightest expenditure of power.

25 The invention consists in the construction and arrangement of the various instrumentalities hereinafter set forth.

In the drawings, Figure 1 is a side elevation of the invention. Fig. 2 is a plan view of the same. Fig. 3 is a detail in elevation of 30 the driving mechanism of the digging mechanism. Fig. 4 is a detail in side elevation of the digging-knives. Fig. 5 is a front view of the same. Figs. 6 and 7 are detail views in perspective of the elevator-buckets. Fig. 8 35 is a detail showing the adjusting mechanism of the elevator.

For the purpose of more clearly describing the machine shown in the drawings we will divide the various instrumentalities into groups 40 with reference to their co-operation in the performance of some particular function, and to the several separate parts of each group we will give a general distinguishing letter. Thus we will distinguish the driving mechanism by the general letter A, the digging mechanism by the letter B, the elevator mechanism by the letter C, the conveying or delivering mechanism by the letter D, the ramming mechanism by the letter E, and the main 45 frame by the letter F.

The digging mechanism consists in the

wedge-shaped downcut-knife B' and the up-cut knives B² B³, with means for forcing the former downward and drawing the latter upward. The means shown in the drawings 55 consists in the heavy screw or worm B³, the lower end of which is inserted within the hollow casing of the knife B', where it is provided with the cross-bar B⁴. The attachment between the screw and knife is by the bolts 60 B⁵, extended from either end of the cross-bar. These bolts extend through the slots B⁷ in the sides of the knife B'. The screw B³ is raised and lowered by the miter-gear B¹⁹, the hub of which is internally threaded to engage the 65 thread of the screw. The gear B¹⁹ is held in position by the brace-rods B²¹, which are bolted to the bearing-plates B²⁰ and to the horizontal beams of the main frame. The plates B²⁰ rest against each side of the hub of the miter 70 B¹⁹ and maintains it in position. On the upper plate B²⁰ are bolted the journal-boxes B²⁴ to receive the ends of the shafts B²³, which carry the pinions B²², that are constantly geared with the miter B¹⁹. The pinions B²² 75 are designed to turn the miter in opposite directions to raise or lower the screw B³. To accomplish this purpose the driving mechanism A is connected by chains to the sprockets B²⁵ B²⁵ on both shafts B²³, on which they are 80 loosely mounted. The face of the sprockets are hollowed out to form a seat for the conical friction-clutches B²⁶, which are splined on the shafts. Suitable levers, having yokes to fit in the grooves B²⁷ on the friction-clutches, 85 are mounted on the frame and joined to each other to cause them to co-operate. Thus by arranging the clutches as shown in the drawings at Fig. 3 it will be seen that as the one clutch is thrown out of engagement the other 90 is thrown in, and the pinions operating in the same direction on opposite sides of the miter B¹⁹ will produce each an opposite movement in the miter from that produced by the other. At their outer ends the shafts B²³ are supported 95 in boxes B²⁸, mounted on the main frame A.

As above mentioned, there are two different styles of knives, B' being what we have styled a "downcut-knife," and the side knives B², 100 which are herein styled "upcut-knives." The downcut-knife is wedge-shaped, as shown at

Fig. 5, and is designed to drive downward through the earth and force it away from the line of cut. For this purpose it is provided with the shoe B^{13} , which may be sharpened and replaced when worn out. The frame of the knife is made up of metal plates and is hollow. The upcut-knives are hook-shaped at their cutting ends, being intended to dig forward and up. They are pivotally connected to the downcut-knife by the pivot-bolts B^{16} and to the bolts B^5 on the screw B^3 by the links B^6 . In their coöperation these down-cut and upcut knives act as follows: Preliminary to starting the machine a hole of the desired depth is dug by hand. The knives are then lowered into the hole and drawn upward. As the screw B^3 starts upward the pull is first imparted to the upcut-knives $B^2 B^2$ by reason of their connection directly to the end of the screw. The downcut-knife B' does not begin to raise until the bolts B^5 reach the top of the slot B^7 . As the pull on the knives $B^2 B^2$ is exerted forward of their pivots B^{16} , their points are drawn forward and upward until the bolts B^5 reach the top of the slots B^7 and the knife B' begins to be raised. The knives $B^2 B^2$ continue in this position until they are drawn out of the earth and the direction of the screw is reversed. When the end of the knife B' strikes the ground, the bolts B^5 are forced to the bottom of the slot B^7 before any force is exerted on the downcut-knife B' . The bolts B^5 , thus descending, the knives B^2 are forced backward by the links B^6 to the positions indicated in dotted lines in Fig. 4 of drawings, thus clearing the front of the knife B' in the downcut. Intermediate the upcut and the downcut the machine is advanced, as will be described, the length of the upcut, so that when the knife B' descends the cutting edge thereof strikes the forward end of the ground which has been separated from the surrounding earth by the knives B^2 . In descending, the knife B' , by reason of its wedge shape, breaks the ground up and throws it onto the buckets of the elevator. At the beginning of the raising of the screw B^3 , when it becomes necessary to project the knives $B^2 B^2$, the knife B' must be prevented from raising. To accomplish this, the slots B^7 , wherein the bolts B^5 operate, and the dogs B^{11} are provided. The dogs B^{11} are mounted between the rollers B^{10} in the frame constructed of the angle-irons B^8 and B^9 . The dogs are provided on their inner ends with brackets B^{12} , in the end of which are friction-rollers B^{13} , that engage the double cams, slots B^{15} , of the brackets B^{14} . The brackets B^{14} are securely mounted on the sides of the screw B^3 , and the vertical length of the slots therein is equal to the length of the slots B^7 , by means of which the knife B' is operated. The slots B^{15} operate in an outward direction for a part of the rise and in an inward direction for the remainder of the rise, driving the ends of the dogs B^{11} into the banks of the ditch and preventing the rise of the knife B' during the first part of the stroke in

which the knives $B^2 B^2$ are projected forward, and then withdrawing the dogs to permit the knife B' to rise with the extended knives B^2 when the bolts B^5 reach the top of the slots B^7 . Thus it will be seen the digging action of these knives is to first sever the earth from the sides and then to strike downward on the section thus severed and cut it away in the line of the ditch to be formed, the driving mechanism being thrown intermittently from one side to the other of the miter B^{19} to cause the screw B^3 carrying the knives to rise and fall.

As above stated, the knife B' , by reason of its wedge shape, severs the ground from that in front and throws it in a segregated condition on the buckets of the elevator mechanism, by which it is carried to the conveying-chute for delivery to the rear of the machine. The buckets C' are connected by continuous chains, which operate over sprockets $C^2 C^2$ at the extremities of the elevator-frame. The upper shaft, on which the bucket-sprockets are mounted, is provided with the driving-sprocket C^3 , suitably connected with the driving mechanism of the machine. The lower shaft is supported in the suspended frame C^4 . On the frame of the machine is mounted the idlers C^6 for adjusting the travel of the buckets with reference to the angle of operation of the digging mechanism. In its operation this elevator mechanism is similar to others of the same class, with the exception of the adjusting mechanism, by which it is raised or lowered to suit the grades of the elevation. This adjusting is accomplished by means of hangings of the shafts carrying the sprockets $C^2 C^2$. These shafts are mounted in suitable bearings supported on the ends of the right and left screws $C^7 C^7$. (See Fig. 8.) These screws are mounted in the end of the frame C^4 and extend through journal-boxes C^{13} . Between the journal-boxes C^{13} and the bottom of the frame C^4 are mounted the miter-gears C^8 , enfolding each screw and meshed into the thread thereof by an internally-threaded hub. These miters C^8 are propelled by the miters $C^9 C^9$, which are geared with the miters $C^8 C^8$, as shown. The miters $C^9 C^9$ are rigidly mounted on the shaft C^{14} , which is journaled in the boxes $C^{13} C^{13}$. This shaft is driven by the sprocket C^{10} and chain C^{11} . The double journals $C^{13} C^{13}$ are bolted to the frame C^4 . These hangings just described are provided at either end of the frame. The sprockets $C^{10} C^{10}$ at either end of the frame are connected by the chain C^{11} , which engages the sprocket C^{12} intermediate the upper and lower sprockets. The sprocket C^{12} is mounted on a shaft which extends across the main frame of the machine and is provided at the outer end with a suitable crank-handle or lever wherewith the operator may turn it. As the sprocket C^{12} is thus turned the chain C^{11} transmits the motion to the sprockets $C^{10} C^{10}$ at both ends of the frame and rotates their shafts, carrying the gears $C^9 C^9$ in the same

direction. The gears rotate the miters C⁸ C⁹, which extend or recede the ends of the screws C⁷ C⁷, according as the rotation is started. In mounting the right and left screws at the two ends of the frame care should be taken that the right-hand screws at both ends are on the same side of the frame.

In some cases I provide the shaft carrying the sprocket C¹² with a graduated scale to indicate the rise or fall of the elevator to suit the grade on which the machine may be operating. Usually, however, this scale cannot be used for the reason that the surface of the ground over which the machine is operating will not permit because of its irregularity.

The buckets C' shown are constructed in section, as shown in Figs. 6 and 7, to allow for lateral adjustment to suit the various dimensions of different ditches. These sections are bolted together, the bolts passing through the perforations c.

As the earth is thrown into the buckets they convey it upward and deliver it upon the chute D, which is built upon a skeleton frame work mounted on wheels D'. The chute D leads over that section of the work where the pipe or sewer is being laid or built and delivers it into the excavation. The chute is detachable from the main frame A of the machine. Near the lower end of the chute the bottom is cut away to permit the insertion of the paddles of the wheel E' of the ramming mechanism. The shaft of the wheel E' is provided with fingers E², set out from the shaft and adapted to extend under the yoke E³ at the top of the tamp E⁴. The tamp E⁴ is mounted in guides E⁵, which are suspended on the braces E⁶ from the frame of the chute D. The tamp E⁴ is provided with the rammer-head E⁷. In its action the dirt running down the chute strikes the paddles of the wheel E' to turn it to operate the shaft carrying the fingers E². The fingers strike under the yoke E³ on the end of the tamp, raising the tamp until the finger passes from under the yoke, when the tamp is allowed to drop. In this manner the earth is rammed at about half-way of the depth of the ditch, so that the surface or hand ramming is rendered easier. These several mechanisms are driven from a common driving mechanism, which also serves as a traction-motor.

The initial source of the power is derived from a gas-engine A', on the driving-shaft of which is the driving-gear A², meshed into the gear A³. The gear A³ is loosely mounted on its shaft and is controlled by the cone-shaped friction-clutch A⁴ to rotate the shaft or independently thereof. Upon the outer ends of the shaft are the sprockets A⁵ A⁶, also loosely mounted on the shaft and controlled by the clutches A⁷ and A⁸. These elements constitute the traction driving mechanism, as the sprockets A⁵ and A⁶ are connected to the driving traction-wheels A¹⁶ and A¹⁷, respectively. In operation the clutch A⁴ is seated hard against the gear A³, causing it to turn the shaft

on which it is mounted. When the drums A⁷ and A⁸ are both engaging their respective sprockets and the shaft is turned, the power is transmitted to the traction-wheels A¹⁶ and A¹⁷ to drive the machine along. If it is desired to turn the machine, one of the clutches A⁷ or A⁸ is released, when its sprocket ceases to drive, and the traction-wheel on its side becomes a pivot on which the machine will turn. To produce a reverse movement of this driving traction mechanism the supplemental shaft, carrying the gears A⁹ loosely mounted thereon, is mounted on the frame and provided with the sprockets A¹⁰ A¹⁰, which are connected with the sprockets A¹¹ A¹¹ on the main shaft. The gear A⁹ is provided with a clutch A¹⁸, similar in construction and action to A⁴, for the purpose of rotating the shaft. With this gear 85 ing the traction may be reversed by releasing the clutch A⁴ and setting the clutch A¹⁸, when the direction of rotation of the main shaft will be reversed. Thus the traction may be controlled to move the machine slightly ahead to 90 turn in either direction or reverse. Upon the main shaft are the sprocket-wheels A¹² A¹², which are connected by chains A¹⁹ A¹⁹ to the sprockets A¹³ A¹³ on the driving-shafts for the screw B³. The sprocket A²⁰ on the main shaft 95 is connected to the sprocket A²¹ on the supplemental shaft carrying the sprockets A¹⁴ A¹⁴, which in turn transmit power to the sprockets C² C² of the elevator.

The forward end of the frame is carried on 100 the rollers A¹⁵ A¹⁵. When the machine is to be transported, the screw B³ is raised until the knives clear the ground. There it is held, or it may be disconnected from the knives and raised out of the miter B¹⁹. The elevator-frame C⁴ is unclamped and the lower end 105 raised and extended level with the ground on a separate truck. The chute-frame is preferably disconnected and the machine is ready for transportation.

No description has been made in this specification of any special lever for throwing in and out of engagement the various clutches, for the reason that I use any known construction.

Having thus described this invention, what I claim is—

1. In an excavator such as described the combination, with a digging mechanism adapted to separate the earth from the sides then to cut it away from in front, of an elevator mechanism to catch the earth when cut from in front and convey it to a raised elevation, a chute to receive the earth from the elevator at the raised elevation and deliver 120 it to a desired point, and a ramming mechanism having a paddle-wheel extending into the said chute to lift and drop a tamp, substantially as described.

2. In an excavator such as described and in the digging mechanism thereof the combination of a wedge-shaped knife adapted to cut downward, with side knives pivotally connected to the wedge-shaped knife and adapted

to swing forward and cut upward, a rod carrying the said knives to raise and depress them, and intermediate connections between the said rod and side knives to force the said 5 side knives forward of the said wedge-shaped knife prior to raising the latter, substantially as described.

3. In an excavator such as described and in the digging mechanism thereof the combination of a wedge-shaped knife adapted to cut downward, with side knives pivotally connected to the wedge-shaped knife and adapted to swing forward and cut upward, a screw carrying the said knives to raise and depress 10 them, intermediate connections between the said screw and side knives to force them forward of the said wedge-shaped knife prior to raising the latter, and a driving mechanism having an internally-threaded wheel to engage the threads of the said screw to raise and 15 lower the same, substantially as described.

4. In an excavator such as described and in the digging mechanism thereof the combination of a wedge-shaped knife adapted to 20 cut downward, with side knives pivotally connected to the said wedge-shaped knife and adapted to swing forward and cut upward, a screw carrying the said knives to raise and depress them, intermediate connections between the 25 said screw and side knives to force them forward of the said wedge-shaped knife prior to raising the latter, dogs set in the wedge-shaped knife, cams on the said screw to throw the said dogs into the bank and with- 30 draw them during the first part of the rise of 35

the said screw, and driving mechanism to engage the threads of the said screw to raise and lower the same, substantially as described.

5. In an excavator such as described and in the elevator mechanism thereof the combination with a series of elevator-buckets joined together to form an endless chain, driving-wheels to propel the said chain of buckets, a frame to support the said driving-wheels, intermediate extensible connections between 40 the said frame and driving-wheels at both ends of the frame and connecting devices between the extensible connections to cause them to operate in unison, substantially as described.

6. In an excavator such as described and in the elevator mechanism thereof the combination with a series of elevator-buckets joined together to form an endless chain, driving-wheels to propel the said chain of buckets, a frame to support the said driving-wheels, screw-shafts intermediate the said driving-wheels and frame at both ends, driving-gears to raise and lower the said screw-shafts, and suitable connecting devices to operate the 45 said driving-gears in unison, substantially as described.

In testimony whereof I have hereunto set my hand, this 26th day of November, 1895, at Stockton, in the county of San Joaquin and 50 State of California.

WILLIAM H. FULCHER.
